UNITED STATES PATENT OFFICE.

FRED. GRIMM, OF COMANCHE, TEXAS.

PLOW.

SPECIFICATION forming part of Letters Patent No. 357,279, dated February 8, 1887.

Application filed October 30, 1886. Serial No. 217,612. (No model.)

To all whom it may concern:

Be it known that I, FRED. GRIMM, a citizen of the United States, residing at Comanche, in the county of Comanche and State of Texas, have invented a new and useful Improvement 5 in Plows, of which the following is a specification.

My invention relates to improvements in plows; and it consists of the peculiar combination and novel construction and arrangement of the various parts for service, substantially as hereinafter fully described, and particularly pointed out in the claims.

The object of my invention is to provide a 15 plow with means whereby the friction upon the landside thereof is very materially decreased, and the draft is lightened to enable the plow to be drawn with less effort by the draft-animal.

20 A further object of my invention is to provide means which can be applied to the plow for the purposes above named at the time of its manufacture, or subsequently thereto after it has been sold, and which can be readily adjusted to cause the plow to run at different depths when in use.

My improvement is capable of vertical adjustment, so that the plowshare and landside will be elevated out of contact with the ground 30 in order to prevent the point from wearing out in transporting or moving it from one field or place to another; and it is furthermore provided with an improved fender and scraper, which prevents the dirt from clogging up and 35 wearing the axle, and keeps the periphery of the wheel clear of mud or other matter that is liable to adhere thereto, all as will be more fully described hereinafter.

In the accompanying drawings, which illustrate 40 a plow embodying my present improvement, Figure 1 is a side elevation taken from the landside of the plow. Fig. 2 is a bottom plan view. Fig. 3 is a longitudinal sectional view on the line xx of Fig. 2. Fig. 4 is an 45 enlarged perspective view of my invention. Fig. 5 is a vertical cross-sectional view of the same on the line yy of Fig. 4.

Referring to the drawings, in which like letters of reference denote corresponding parts 50 in all the figures, A designates the standard, which is to be bolted or otherwise attached in any suitable manner to the beam of a plow. A point, B, of any approved pattern, and a mold-board, B', are connected to the lower end

of the standard in the ordinary manner, and 55 the forward end of the point is braced by a landside, D, which is also attached or connected to the standard. The landside is made in two sections—a front and rear section—which are joined or connected together at about 60 the point where the horizontal foot a of the standard A is connected thereto, this foot a being curved and extended forward beneath the point and bearing against the inner sides of the sections of the landside. The foot covers 65 the joint between the sections of the landside, and the latter is bolted thereto to provide a very firm and rigid structure, the heads of the bolts being countersunk in suitable openings in the outer face of the landside, so as to lie flush 70 with the said outer exposed face of the landside, which acts upon the soil.

The point and mold-board are braced by a plate or strap, E, which is arranged on the inner concealed sides thereof and suitably secured to the same, and a horizontal brace, F, extends from the landside to the mold-board to brace the outer edge of the latter, the outer end of the brace F being bent at f , to provide 75 an arm which extends across the joint between 80 the mold-board and point to further brace and strengthen the said point and mold-board.

The rear terminal end of the landside is concaved or curved, as at g , and a roller or wheel, G, is arranged in close proximity to 85 the said curved terminal end of the landside, as shown. This roller or wheel is arranged in line with the landside, and the outer surface thereof is flat and lies flush with the exposed outer surface of the landside, so that as the 90 plow is drawn along over the field this roller or wheel will not retard the progress of the same.

The wheel or roller is journaled in a bracket-plate, H, which is arranged to one side of the 95 landside, on the inner concealed side thereof. The rear end of the landside can be bent at the time of its manufacture to provide or form the bracket-plate, or the latter plate can be riveted to the landside, or welded thereto, after 100 it has been sold, as will be very readily understood. In the accompanying drawings I have shown this bracket-plate bolted to the rear end of the landside, and the rear end of the bracket-plate extends or projects in rear 105 of the landside, as shown. This extended rear end of the bracket-plate is provided with a segmental or curved slot, h , through which an

axle, J, extends, that carries the roller or wheel G. The outer end of the axle or shaft J is passed through the central opening, g' , in the roller or wheel G, and this opening of the 5 wheel is beveled or countersunk on the outer side thereof, in which the beveled head j of the axle or shaft J fits and lies flush with the outer face of the wheel, as clearly shown in Figs. 2 and 5 of the drawings. This shaft or 10 axle J is rounded at the point where the wheel or roller turns or revolves thereon, and the axle is squared, as at j' , at the point where it passes through the segmental slot of the bracket-plate, so as to prevent the shaft from part- 15 taking of the rotary motion of the wheel or roller when the plow is drawn across the field. The extreme inner end of the shaft or axle is again rounded and threaded externally, and on this threaded portion of the shaft is fitted 20 a binding-nut, J', which bears upon a washer, K, that is interposed between the nut and the bracket-plate, as clearly shown.

The bracket-plate has a fender, L, bearing upon the upper edge thereof, and which is 25 curved upwardly therefrom and extends over the periphery of the roller or wheel G. This fender is of greater width than the wheel and the bracket-plate, so as to conceal the upper edges thereof and prevent the dirt or soil that 30 is loosened by the plow from passing between the wheel and bracket-plate to the axle, which is liable to cause undue friction on the axle and soon wear the latter away. The rear end of the fender is bent or curved downwardly 35 and beveled, so that it will come in contact with the periphery of the wheel, or nearly so, and thus perform the additional functions of a scraper to clear the wheel from accumulations of earth and other matter thereon. The 40 fender is further provided with a downwardly-extending inclined arm, M, which is provided at its lower end with a transverse opening, m , which aligns with the slot of the bracket-plate H, so that the squared end of the axle or shaft 45 J will pass through the said transverse opening. The said lower end of the arm M is fitted between the washer and the bracket-plate, and the fender is thus braced by the inclined arm being connected to the bracket-plate by 50 the same axle which carries the roller or wheel G.

The wheel G is of greater diameter than the width of the landside of the plow, so that the upper and lower edges of the wheel are projected beyond corresponding edges of the landside; and by thus extending the periphery of the wheel below the lower edge of the landside the latter is elevated out of contact with the earth to decrease the friction thereon and 60 very materially lessen the draft on the plow.

The fender is formed separate from the bracket-plate, and the opening in the lower end of the brace-arm thereof is made square in form, so that the squared portion of the 65 shaft or axle will pass therethrough, whereby when the axle is raised or lowered in the slot of the fixed bracket-plate the arm and the

fender will be adjusted with the wheel, and the fender thereby occupies the same relative position to the wheel at all times, so as to protect 70 the same and clear mud and other accumulations therefrom.

The operation of my invention will be readily understood from the foregoing description. When it is desired to move the plow from one 75 field to another, the shaft or axle is lowered in the slot of the fixed bracket-plate by loosening the binding-nut, and thereby depressing the wheel below the lower edge of the landside of the plow, so that when the device is in 80 motion the periphery of the wheel will ride upon the ground and the lower edge of the landside will be elevated out of contact therewith, the fender being moved or adjusted simultaneously with the roller or wheel. When 85 the plow reaches the field, the axle is adjusted to the desired height in order to regulate the depth to which the plow will enter the ground; and as the plow is drawn through the ground the landside is slightly raised by the roller or 90 wheel G to lessen the friction on the landside, the said wheel being arranged flush with the outer side of the landside to prevent the wheel from retarding the progress of the plow.

I do not desire to confine myself to the exact details of construction and form and proportions of parts herein shown and described as an embodiment of my invention, as I am aware that changes therein can be made. 95

Having thus fully described my invention, 100 what I claim as new, and desire to secure by Letters Patent, is—

1. An attachment for plows, comprising a detachable bracket-plate secured to one side of the landside of a plow, and having a slot, 105 and a wheel or roller arranged on one side of the plate and in line with the landside, the shaft or axle of the wheel or roller passing through the slot of the plate and having the threaded inner end provided with a nut, substantially 110 as described, for the purpose set forth.

2. In combination with a landside of a plow, a bracket-plate secured thereto, a roller or wheel in line with the landside, and a fender above the wheel, having the arm connected 115 with the axle of the wheel, substantially as described, for the purpose set forth.

3. An attachment for plows, comprising a bracket-plate having the slot, the roller or wheel, the shaft or axle of the wheel or roller 120 passing through the slot of the bracket-plate, a fender having the inclined brace-arm, and a nut fitted on the threaded end of the shaft and clamping the axle, the fender-arm, and the bracket-plate to the landside of a plow, 125 substantially as described, for the purpose set forth.

In testimony that I claim the foregoing as my own, I have hereto affixed my signature in presence of two witnesses.

FRED. GRIMM.
